STAND FOR TELEVISION RECEIVERS

William Remstein, Syracuse, N. Y.

Application September 9, 1953, Serial No. 26,751

Term of patent 14 years

(Cl. D33—14)

To all whom it may concern:

Be it known that I, William Remstein, a citizen of the United States of America, residing at Syracuse, in the county of Onondaga and State of New York, have invented a new, original, and ornamental Design for Stand for Television Receivers, of which the following is a specification, reference being had to the accompanying drawing, forming part thereof, in which: The single figure is a perspective view of a stand for television receivers, showing my new design.

I claim:

The ornamental design for a stand for television receivers, substantially as shown.

WILLIAM REMSTEIN.
